CATHODE-COUPLED WIDE-BAND
AMPLIFIER

Alfred C. Schroeder, Feasterville, Pa., assignor to
Radio Corporation of America, a corporation of
Delaware

Application December 28, 1944, Serial No. 570,176

6 Claims. (Cl. 179—171)

1

My present invention relates in general to amplifier circuits, and more particularly to such circuits utilizing triode tubes in cathode-coupled relation for amplifying a wide band of high frequencies such as may be employed for example in the transmission and reception of television signals.

With the advent of television and the need of wide-band amplifiers of radio frequencies (RF) and intermediate frequencies (IF), circuit requirements became such that high plate impedance obtained with multi-grid tubes was of relatively little importance. In fact, the wide band of frequencies to be amplified dictates low Q and low impedance circuits. However, in order to obtain the required gain with low impedance circuits, it is necessary that high G_m (transconductance) tubes be used. For certain applications, such as the input stages of wide-band, high-gain receivers, triodes are more desirable than pentodes because of their inherently lower noise characteristics. A low impedance circuit frequently used is the cathode output or cathode follower circuit. It has been proposed to use a circuit of this type in conjunction with a conventional or grounded-cathode amplifier, but such a circuit, besides requiring the same number of circuit elements as two amplifier stages of conventional type, has heretofore been used with a pentode tube as the grounded-cathode amplifier. In some cases this dual stage does not provide adequate stability, and also does not provide better noise characteristics than conventional circuits employing pentode tubes.

I have discovered that by combining a cathode-output and a cathode-input stage using a single twin-triode tube, a high-gain, wide-band amplifier stage is obtained which compares favorably with a pentode stage with respect to gain, stability and economy, while it has far superior noise characteristics. The new circuit, which I have called the "cathode-coupled twin-triode" amplifier, provides greater flexibility than conventional amplifier circuits, and can be used for RF, IF, video, converter, or detector services.

It is accordingly an object of the present invention to provide a wide-band, stable amplifier having better signal-to-noise ratio than multi-grid tube amplifiers.

A further object of the invention is to provide an amplifier that has output to input shielding comparable to that of a screen grid or pentode tube but with relatively lower input capacity.

A more specific object of the invention is to provide a pair of cathode-coupled triode ampli-

2

fiers in which the coupling means is constituted by a high frequency choke coil and in which the grid biases and anode potentials are so chosen that linear amplification occurs over a wide range of input signal voltages.

The novel features characteristic of my invention are set forth with particularity in the appended claims. The invention itself, however, both as to its organization and mode of operation together with further objects and advantages thereof, will best be understood by reference to the following description taken in connection with the accompanying drawings in which:

Figs. 1 to 3 illustrate various modifications of wide-band cathode-coupled triode amplifiers according to the invention.

Referring to Fig. 1 there is shown at 1 an electron discharge tube commonly known as a twin-triode, a suitable type being the "6J6." It will be understood, however, that the invention may be practiced with equally good results using two separate triode tubes, in which case each of the two sections T_1 and T_2 would be enclosed in its own evacuated bulb or container. The grid 2 of the first tube section T_1 is connected to an input terminal 3, and between said grid or input terminal and a second input terminal 4 which is grounded there is connected the usual grid leak resistance 5. A suitable source of RF or IF signals is adapted to be connected to the input terminals 3—4. I have found in practice that the cathode-coupled twin-triode amplifier disclosed herein is admirably suited as the first IF amplifier stage of a superheterodyne receiver in which case the input terminals 3—4 would be connected to the output of the converter stage.

The cathode 6 of section T_1 is connected to input terminal 4 or ground through a radio frequency (RF) choke 7 and the anode 8 of this section is connected for high frequencies to ground by way of condenser 9, the anode being energized from a source of direct current represented by B_+ . The portion of the circuit just described constitutes a cathode-follower which serves to drive the second section T_2 functioning as a grounded-grid amplifier. The cathode 10 of the latter section, like the cathode of the first section, is connected to the high potential end of coil 7 so that the coil, which is the output load impedance in the cathode circuit of the first section and the input impedance of the cathode circuit of the second section, forms the sole coupling means between the two sections.

The grid 11 of the second section T_2 has a direct connection to ground, and the anode 12

has connected to it a load impedance, shown by way of example as a primary 13 of an output transformer T₂, the secondary 14 of which feeds an RF (or IF) stage 15 which may be similar to the stage just described employing tube 1. The condenser 16, shown dotted, since it may represent only the distributed capacity of winding 13, strays and tube capacities, serves to tune the output circuit of the stage to the center frequency of the band of frequencies to be amplified, which may, for example, be 4 to 6 mc. (megacycles) wide. Resistor 17 shunted across the transformer secondary 14 plus the plate resistance of T₂ serves to load the transformer to give the proper band width.

The cathode coupling coil 7 should have an impedance that is high compared to the internal input impedance of the grounded-grid stage T₂ over the frequency band to be amplified and serves to eliminate the apparent reactive (capacitive) component in the cathode circuit by parallel resonance with the distributed cathode to ground capacity 18, thereby improving the signal-to-noise ratio and the gain. Because of the low cathode input impedance of T₁ and T₂ this resonant circuit has a very low Q and hence a very wide band. This makes the value of the choke uncritical. I have used one of approximately 20 microhenries with very satisfactory results.

It is important for the proper operation of the circuits described herein that the grid bias and plate voltage be selected of such values that no limiting or clipping takes place. Although in Fig. 1, the grids of both sections operate at zero bias, the plate voltage is chosen of suitable value to avoid the limiting action mentioned.

The circuits of Figs. 2 and 3 are fundamentally similar to the circuit of Fig. 1 except that in Fig. 2 there is included in the cathode circuit, in series with the high frequency choke, the usual self-biasing resistance and shunt condenser network 19 for varying the gain of the amplifier, and in Fig. 3 the gain may be varied by changing the D. C. voltage on either, or both, of the grids by means of a voltage derived for example from an A. V. C. system, as is well known in the art.

With a type 6J6 tube I have used 70 volts on the plate with the grids at 0 and no cathode bias (Fig. 1), and about 125-150 volts on the plate with the grids at 0, and about a 50-ohm cathode resistor unbypassed (Fig. 2).

The gain of the wide-band amplifier of the cathode-coupled twin-triode type herein described is equal to

$$\frac{G_m}{4\Delta\omega C_0} \sqrt{\frac{C_0}{C_1}}$$

which is favorably comparable to the gain

$$\frac{G_m}{2\Delta\omega C_0} \sqrt{\frac{C_0}{C_1}}$$

obtained for conventional grounded-cathode amplifiers, particularly since the input capacity (C₁) is reduced by a factor of

$$\left(1 - \frac{1+2\Delta\omega C_0 r_p}{4\Delta\omega C_0 r_p}\right)$$

by reason of degeneration of the grid to cathode capacity, G_m being the transconductance of each tube section, C₁ and C₀ the input and output capacities, respectively r_p the plate resistance, and Δω being equal to 2πΔf. The advantage of a lower capacity is that since the total capacity across the circuit is what limits the gain times

70 75

band width, the lower the capacity the higher the gain for a given band width, or the wider the band for a given gain.

The circuit is economical since a coil (Figs. 1 and 3) or a coil and a resistor (Fig. 2) are the only coupling elements required between the two sections when using a twin-triode or between two tubes when using separate tubes. The resistor and by-pass capacitor customarily required in a screen supply are eliminated. Since the plate currents in the two triode-units swing in opposite directions, the total plate load tends to remain uniform, and subsequent similar stages have little influence on each other such as might result from varying load on the plate supply.

While I have shown and described a preferred embodiment of my invention, it will be understood that various modifications and changes will occur to those skilled in the art without departing from the spirit and scope of this invention. I therefore contemplate by the appended claims to cover any such modifications as fall within the true spirit and scope of my invention.

What I claim is:

25 30 35 40 45 50 55 60 65 70 75 80

1. A wide-band high-frequency amplifier comprising a cathode-follower stage coupled to a cathode-input, grounded-grid stage, the coupling means between said stages being constituted by an inductance having an impedance at the frequencies to be amplified which is high compared to the internal input impedance of the grounded-grid stage.

2. A wide-band high-frequency amplifier comprising a cathode-follower stage coupled to a cathode-input, grounded-grid stage, the coupling means between said stages being constituted by a high frequency choke connected between the cathodes of both stages and ground, said choke resonating with the capacitance between the cathodes and ground over a wide range of frequencies.

3. A wide-band high-frequency amplifier comprising a cathode-follower stage coupled to a cathode-input, grounded-grid stage, the coupling means between said stages being constituted by an inductance which is common to the cathode circuits of both stages, the value of said inductance being high compared to the input impedance of the grounded-grid stage at the frequencies to be amplified and being of the order of 20 microhenries.

4. A circuit for the amplification of a wide band of high frequencies comprising first and second electron discharge paths each constituted by a cathode, a grid and an anode, a source of high frequencies connected between the grid of the first discharge path and ground, a common reactive impedance connected between said cathodes and ground, a ground connection to the grid of the second discharge path, an output impedance connected between the anode of the second discharge path and a source of anode potential, and a high frequency ground connection to the anode of the first discharge path, the biases on the grids and the potentials on the anodes being chosen of such values that the circuit functions as a linear amplifier over a wide range of input signal voltages.

5. A circuit for the amplification of a wide band of high frequencies comprising first and second electron discharge paths each constituted by a cathode, a grid and an anode, a source of high frequencies connected between the grid of the first discharge path and ground, a common reactive impedance connected between said cathodes and ground.

odes and ground, a ground connection to the grid of the second discharge path, an output impedance connected between the anode of the second discharge path and a source of anode potential, and a high frequency ground connection to the anode of the first discharge path, said common cathode impedance having a value that is high compared to the input constituted by the grounded grid and its cathode, over the band of frequencies to be amplified.

6. A circuit for the amplification of a wide band of high frequencies comprising first and second electron discharge paths each constituted by a cathode, a grid and an anode, a source of high frequencies connected between the grid of the first discharge path and ground, a common reactive impedance connected between said cathodes and ground, a ground connection to the grid of the second discharge path, an output impedance connected between the anode of the second discharge path and a source of anode potential, and a high frequency ground connection to the anode of the first discharge path, said common

cathode impedance having a value that is high compared to the input constituted by the grounded grid and its cathode, over the band of frequencies to be amplified, and the biases on the grids and the potentials on the anodes being chosen of such values that the circuit functions as a linear amplifier over a wide range of input signal voltages.
